FIG. 6.

United States Patent Office.

HOSEA BALL, OF NEW YORK, N. Y.

Letters Patent No. 103,825, dated June 7, 1870.

IMPROVEMENT IN ORE-SEPARATORS.

The Schedule referred to in these Letters Patent and making part of the same.

I, HOSEA BALL, of the city, county and State of New York, have invented an improved Ore-Separator, of which the following is a specification.

Nature and Objects of the Invention.

My apparatus is designed to sort into various qualities, according to gravity, metallic ores reduced into a comminuted condition. The slimes from the stamps, for instance, are discharged in regulated quantities into an ascending body of water, which carries the relatively lighter portions to one point of discharge, and allows the heavier to sink into another receptacle.

The special points of invention which distinguish my apparatus from those which have preceded it are:

First, the distribution of comminuted ores, of varying degrees of fineness, to separate trunks, in each of which the rate of motion of the column of water is adjusted to the specific requirements of the grade of ore in said trunk.

Second, the emission of the comminuted ore through an annular throat at the end of the feed-pipe, at which point it meets the upward current of water, which thence flows in an annulo-cylindrical trunk within an outer casing, or downeast trunk of similar character.

Third, the co-axial arrangement of the downeast water-trunk, upcast water-trunk, and central feed-cylinder, giving a compact form, and one not subject to induce irregular currents, or such as may have unequal force at different parts of their course.

Description of the Accompanying Drawing.

Figure 1 is a side elevation, partly in section, of my apparatus, showing four trunks operating in concert upon different grades of material from the perforated cylinder above.

Figure 2 is a view on the plane of the line *a b*, fig. 1, showing the upper works in section, and one of the trunks in elevation.

Figure 3 is a vertical central section of one of the trunks, on a plane cutting through both of the discharge-spouts, on the line *c d*, fig. 5.

Figure 4 is a view in which the outer or downeast water-trunk is in section, but the interior portions are in elevation. Its line of section is the dotted line *e f*, fig. 6.

Figure 5 is a top view, looking down on the trunk.

Figure 6 is a horizontal section on the line *g h*, figs. 3 and 4.

General Description.

The upper portion of the apparatus, which distributes the ore or slimes into the trunks, is exhibited in figs. 1 and 2, and to those views the first part of the description will particularly refer.

A is a spout or pipe, which conducts the slimes from

the stamping-mills or grinder, and delivers them into the smaller end of the perforated cylinder *B*. The perforations at the induction-end are finer, or the meshes of the wire-cloth are smaller, as the case may be, than at any other point, becoming coarser toward the larger end of the cylinder. Different sections of the length of the cylinder have different grades of fineness, so as to distribute to each trunk an approximately even quality of ore.

The cylinder has a rotary motion by means of a crank or band.

C is a water-pipe, with branches *c' c'*, which convey water from the tank *c* into the cylinder, and distribute it in sprays through numerous holes. The entering slimes are supposed to have water enough to convey the finer particles through the meshes or apertures near the entering end of the cylinder, and the pipe *c* is shown as destitute of holes for a portion of its length.

Beyond this closed portion the pipe is perforated, as is also the companion pipe *c* which enters from the other end of the cylinder, the object being to afford a sufficient amount of water to encourage the passage of the various grades of slimes or comminuted ores through the meshes of varying openness, as they are successively traversed.

Fig. 1 shows four trunks in position to catch the results of the sifting arrangement described, but I do not limit myself to any particular number.

The shaft *b* passes through the cylinder *B*, and is supported in such a way as not to interfere with the passage of the pipes which convey the water.

The slimes which pass from the sifting or grading-cylinder *B* are received in the successive hoppers *D D' D''*, which convey the graded qualities to the respective trunks *E E' E''*, in each of which the said ore is subjected to the action of water, to sort it according to gravity into two parcels. It will be apparent from the description that the trunk *E* will have the finest quality and *E''* the coarsest, the former being perhaps an almost impalpable powder, and the latter having particles perhaps as large as cubes of one-eighth inch on their sides.

The ore and water falls into the central cylinder *F* of the washer, and is thence distributed into the upcast water-trunk *G*, passing against the periphery of the cone or valve *H*, which regulates the feed, and which is adjustable vertically by the nuts *h h'*, so as to vary the width of the annular opening according to the size of the particles of ore, and the other possible requirements of the process, such as those resulting from comparative poverty or levity of the gang, &c.

Each trunk is supplied with water by means of a pipe, *K*, from the tank *C'*. The water is received in the funnel *I* belonging to the tank, (see figs. 4 and 1,)

and occupies the outer annulo-cylindrical spaces *J*, and the lower part *J'* of the trunk. It thence passes upwardly in an even current around the edge of the cylinder *G*, is deflected by the inverted cone *H'*, and strikes against the ore as it issues from the annular opening bounded by the cone *H* and the lower edge of the cylinder *F*.

The effect of the upward column of water is to carry up all the particles which have less than a certain specific gravity, or which present a certain amount of surface to the current, while those of a heavier description will sink to the bottom of the tank *J*. The said lighter particles flow out at the spouts *L*, and are treated according to their character. The heavier particles are removed, as occasion may require, from the man-hole or shovel-hole *M*.

The description just given applies in general terms to each of the trunks, the operation proceeding simultaneously in each, but a variation occurs in the area of opening around the valve *H*, and, also, in the amount of water afforded to each trunk, according to the grade of the ore under treatment.

The valve *H* may be of other forms than that represented, the annular character of the throat or feed-opening being maintained. I do not desire to confine myself to any particular form of valve.

The tank *C* has an overflow-pipe, and the water in the tank is thereby kept at a constant height, so that its regulation may remain uniform, when once adjusted.

The co-axial arrangement of the cylinders *J G F*, forming, respectively, the downcast and upcast water-

ducts, and the ore-supply pipe, serve to distribute the water to the ore in an equable manner, reasonably free from counter-currents and special determination of the water to particular points. Were the water introduced at one or several points it would produce eddies and unequal action at the point of contact with the ore, and would thus fail to exert a uniform action thereupon over the whole sectional area, at which takes place the critical selection by gravity, determining the destination of the individual particles.

Claims.

What I claim as new is—

1. The cylinder *B*, having meshes or perforations of varying fineness at different parts of its length, and acting in connection with the necessary ore-carrying spout and water-pipes, to distribute the graded ore to different trunks, substantially as described.
2. The combination of the adjustable valve *H* with the co-axial cylinder *J G F*, operating, as described, to emit an annular stream of ore against an ascending current of water, for the purpose stated in the specification.
3. The co-axial arrangement of the cylinders *J G F*, constructed and operating as described.

To the above specification of my improvements in ore-separators I have signed my hand this 7th day of May, A. D. 1870.
